INSULATED PITCHER

John S. Cummings, Nashville, Tenn., assignor to
Aladdin Industries, Incorporated, Chicago, Ill.

Filed Feb. 25, 1974, Ser. No. 445,056

Term of patent 14 years

Int. Cl. D7—01

U.S. Cl. D7—64

FIG. 1

FIG. 2

FIG. 3

FIG. 4

FIG. 5

FIG. 1 is a side view of an insulated pitcher showing my new design, the side opposite being a mirror image thereof;

FIG. 2 is a front view of the insulated pitcher;

FIG. 3 is a sectional view along the lines 3—3 of FIG. 2 showing the interior conformation of the insulated pitcher;

FIG. 3 is a rear view of the insulated pitcher partially in section in order to show the interior conformation; and

FIG. 5 is a top view of the insulated pitcher.

The bottom is substantially plain.

I claim:

The ornamental design for an insulated pitcher, as shown and described.
